UNITED STATES PATENT OFFICE.

AMBROSE GOOSLIN, OF BLACKBERRY CREEK, KENTUCKY.

PIPE-GRAPPLE.

1,144,590.

Specification of Letters Patent. Patented June 29, 1915.

Application filed July 10, 1914. Serial No. 850,160.

To all whom it may concern:

Be it known that I, AMBROSE GOOSLIN, a citizen of the United States, and a resident of Blackberry Creek, in the county of Pike 5 and State of Kentucky, have invented certain new and useful Improvements in Pipe-Grapples, of which the following is a specification, reference being had to the accompanying drawings, forming a part of this 10 specification.

This invention relates to certain new and useful improvements in grapples, especially adapted to be used in removing pipe, casing and tile from wells, and my invention consists in the novel features hereinafter 15 described.

The primary object of my invention is to provide a pipe grapple of a simple, durable and compact construction, which shall be 20 capable of accurate and convenient manipulation in the removing of tubing and casings from wells.

With these and other objects in view, the present invention consists in the combination and arrangement of parts as will be hereinafter more fully described and finally pointed out in the appended claims, it being further understood that changes in the specific structure shown and described may 30 be made within the scope of the claims, without departing from the spirit of the invention.

In the accompanying drawings forming a part of this specification, and in which 35 like numerals of reference indicate similar parts in the several views: Figure 1 shows a sectional view of a pipe showing my grapple arranged therein. Fig. 2 is an enlarged sectional detail of the grapple. Fig. 3 shows 40 a perspective detail of one of the spur bars. Fig. 4 shows a sectional view through the carrying member showing a slight modification in connection with the means for securing the supporting ring 14. Fig. 5 is a 45 section on line 5, 5, of Fig. 4. Fig. 6 is a section on line 6, 6, of Fig. 4.

In my present invention I provide a pipe grapple arranged to be used in connection with different sizes of pipes or casing. The 50 construction is such that when the spur bars are spread to engage the maximum sizes of pipe or casing, the spur bars all have their ends resting against a solid structure so

that there is no possibility of the carrying member collapsing under strain.

55

In the drawings the numerals 10, 10 represent two plates which are held in parallel spaced relation and form the carrying member. At one end these plates are held in spaced relation by means of an intervening 60 bar 11 and at the opposite ends by means of the intervening bar 12. As shown in Figs. 1 and 4, each plate 10 is provided with a neck extension 10'. In Figs. 1 and 2 the two plate members are of one strip of metal 65 provided intermediate of their ends with a loop 9' arranged to receive a ring 14. In Fig. 4, the plates 10, 10 are of separate sheets and instead of a loop 9' are provided with an opening 8' through which the ring 70 14 passes. At their upper ends the plates 10, 10 are secured to the intervening bar 11 by means of the rivets *a*, and at their lower ends the intervening bar 12 is held in position by means of the rivets *c*.

75

Near their lower ends the plates 10 are provided with two oppositely positioned studs 9 which pivotally support the two spur bars 16, 16 each of which has its lower end *u*, chamfered or extending obliquely, so 80 that these chamfered ends are stopped against the lower intervening bar 12, this bar 12 thus limiting the outward movement of the spur bars 16. Each spur bar has its upper end *d* pointed and near each upper 85 end is provided with an opening *e*, the points *d* being at the outer edge as clearly shown in Fig. 2.

In order to normally hold the spur bars 16 in their outwardly spread position and 90 against the intervening stop bar 12, I provide the approximately U-shaped spring *B*, which is of a width equal to the width of the spur bars 16 and is held between the two plates 10, 10 in the manner shown in 95 the drawings.

Secured to the outer face of each plate 10 is a channel iron 15, these channel irons being secured to the plates 10 by means of the rivets *a*, *b* and *c*, as clearly shown in 100 Fig. 4.

Near its lower end each channel iron carries a stud *x*, these studs being positioned in alinement with the studs 9 which support the spur bars 16. The studs *x* support the 105 spur bars 18 which also have the points *d*,

and near their upper ends being provided with an opening *e*. The chamfered ends *u* are arranged to be stopped in one position against the inner faces of the angle irons 15, as shown in Fig. 4. In order to hold these spur bars 18 in their outwardly directed positions, so that their chamfered ends normally rest against the inner faces of the angle irons 15, I provide the approximately U-shaped spring A. This spring is passed through suitable registering openings *z* formed within the plates 10 and the bases of the angle irons 15, as shown in Figs. 2 and 4. The openings *z* containing the spring A are so arranged that the same come at a point immediately above the spring B, so that after once placing the spring A in position this spring will rest directly upon the spring B and hold the same in secure position between the plates 10, as will be understood in referring to Figs. 2 and 4.

Secured to the upper ring 14 is a suitable carrying strand F, while secured to each spur bar 16 and 18 is the lower end E of an operating strand D.

As shown in Figs. 4 and 2, the lower end of the carrying member is provided with a ring 13, to which is secured a member 20 extending from the weight 21. This weight is necessary at times in order to insure the grapple properly descending within the pipe or duct. In lowering the grapple the same may be lowered by means of the operating member D, so that the lower ends E will carry the weight of the grapple insuring the spur bars 16 and 18 being held against the carrying member. This insures the ready descent of the grapple. As soon as the member D is released and the grapple is held by means of the member F, the spur bars are forced outward by means of the springs A and B. Then in raising the grapple by means of the strand F, the entire casing may be raised and lowered as the ends of the spur bars will positively engage the inner face of the casing.

When the spur bars are extended their full limit, the ends all rest against a solid structure as will be understood in referring to Figs. 2 and 4.

It is of course understood that grapples embodying my invention may be made in various sizes.

The grapple is simple and inexpensive in construction and both durable and efficient in operation, and can be readily lowered within a tube or casing to positively engage the same.

Having thus described my said invention what I claim as new and desire to secure by United States Letters Patent is:

1. A device of the character described, comprising a carrying member including

two plates held in parallel spaced relation, 65 two oppositely positioned spur bars pivotally held between said plates, a spring to normally force said spur bars outward, two oppositely positioned channel irons secured to the outer faces of said two plates said 70 channel irons and carrying plates having oppositely positioned registering openings, a spur bar pivotally secured to each angle iron, and a spring passing through said 75 openings to force said last mentioned spur bars outward said last mentioned spring holding said first mentioned spring in position, as and in the manner set forth.

2. A device of the character described, comprising a carrying member including 80 two plates held in parallel spaced relation, two oppositely positioned spur bars pivotally held between said plates, a spring to normally force said spur bars outward, two oppositely positioned channel irons secured to the outer faces of said two plates said 85 channel irons and carrying plates having oppositely positioned registering openings, a spur bar pivotally secured to each angle iron, means limiting the outward movement 90 of each of said spur bars, and a spring passing through said openings to force said last mentioned spur bars outward said last mentioned spring holding said first mentioned 95 spring in position, as and in the manner set forth.

3. A device of the character described, comprising a carrying member including 100 two plates held in parallel spaced relation, two oppositely positioned spur bars pivotally held between said plates, a spring to normally force said spur bars outward, two oppositely positioned channel irons secured to the outer faces of said two plates said 105 channel irons and carrying plates having oppositely positioned registering openings, a spur bar pivotally secured to each angle iron, an operating strand secured to said 110 spur bars and a spring passing through said openings to force said last mentioned spur bars outward said last mentioned spring holding said first mentioned spring in position, as and in the manner set forth.

4. A device of the character described, comprising a carrying member including 115 two plates held in parallel spaced relation, an intervening link secured between said plates near their lower ends, two oppositely positioned spur bars pivotally held between said plates each having its pivoted end 120 chamfered and arranged in one position to stop against said link, a spring to normally force said spur bars outward, two oppositely positioned channel irons secured to the outer faces of said plates said channel 125 irons and carrying plates having oppositely positioned registering openings, a spur bar pivotally secured to each angle iron each

ending in a chamfered end arranged to stop in one position against its connected channel iron, and a spring passing through said openings to force said last mentioned spur bars outward said last mentioned spring held above said first mentioned spring, all arranged as and in the manner set forth.

In testimony whereof I affix my signature, in the presence of two witnesses.

AMBROSE GOOSLIN.
